DECORATIVE HATS

Mary F. Woodward and Madelyn A. McQueen,
Kansas City, Mo.

Application June 16, 1954, Serial No. 437,111

6 Claims. (Cl. 2—177)

This invention relates to decorative hats particularly designed to be worn by women and children at special occasions where striking color effects are desired.

It is an object of this invention to provide a decorative hat structure for women and children which is highly ornamental to the wearer, which can be made from numerous and varied sheeted materials in harmonious and contrasting colors, which can be economically fabricated and assembled for sale at modest cost, and which is particularly adapted for wear in pageants and plays and at garden parties, weddings and like special occasions.

In the accompanying drawings,

Fig. 1 is a perspective view of a decorative hat made in accordance with this invention as it would appear on the head of a wearer;

Fig. 2 is a plan view of the brim forming frame member which provides the frame structure for the hat body;

Fig. 3 is a plan view of a strip of sheet material from which the inner facing for the brim forming frame member may be formed;

Fig. 4 is a plan view of a strip of sheet material from which the top facing for the frame member may be formed;

Fig. 5 is a plan view which illustrates the manner in which the under and top facing strips are sewn together to encase the frame member and provide a hat crown;

Fig. 6 is a transverse cross section of the hat as it would appear when viewed along line 6—6 of Fig. 5;

Fig. 7 is a modified form of brim forming frame member used to make a decorative hat with off-set crown;

Fig. 8 is a plan view of a strip of sheet material which is cut and shaped to provide the under facing for the frame member shown in Fig. 7; and

Fig. 9 is a plan view of a strip of sheet material shaped to provide the top facing for the brim forming frame member shown in Fig. 7.

Similar reference characters refer to similar parts throughout the several views of the drawings and specification.

The brim forming frame member 1 as shown in Fig. 2 may be made from numerous different materials which is preferably relatively stiff but formable into artistic shapes where an inexpensive hat to be worn only on a single occasion or for limited wear only is desired, the frame member 1 may be made from a cardboard or fiberboard, and where a more lasting hat is desired, the frame member 1 may be made from plastic or composition sheet material. The outer periphery 2 of the frame member may be generally circular, elliptical or polygonal in shape, depending upon the decorative values desired. The frame member 1 has a hole 3 therein generally shaped and sized to conform with the head of the wearer. The modified form of brim forming frame member 1' shown in Fig. 7 has its head receiving opening 3 placed in an off-center position to provide a brim of unbalanced width, with the brim section of greatest width worn to extend either forwardly or rearwardly of the wearer's head.

The under facing strip 4 and the top facing strip 5 as

2

shown in Figs. 3 and 4, and the under and top facing strips 4' and 5' shown in Figs. 8 and 9 may be made from numerous and varied flexible sheet materials, depending upon the quality of hat desired. Materials adapted for this purpose may comprise textile fabrics such as cotton, wool or synthetic fiber textiles, woven fibers and straw, of any desired grade and quality. Where the hat is to be worn for a single or special occasion use only, the under and top facing sheets 4—4' and 5—5' may be made of crepe paper or other inexpensive fibrous and plastic sheeting materials. The under and top facing sheets can advantageously be made in contrasting but harmonious colors such as pink and blue, red and white, light green and orange, yellow and blue, or any other color combinations suitable for the festive occasion at which the hat is to be worn.

The under and top facing sheets are preferably substantially wider than the width of the brim forming part of the frame member as defined between its inner peripheral margin of the head opening 3 and its outer peripheral margin 2, so that the facing strips as applied to the frame member provide skirt sections extending beyond the outer periphery 2 of the frame member, and crown portions extending around the inner perimeter of the head opening 4—4' in the frame member. The under facing strip 4—4' is also preferably somewhat wider than the top facing strip 5—5'. Where the head opening 3 is positioned at the approximate center of the frame member 1 as shown in Fig. 2, the inner and outer facing strip 4 and 5 may be made substantially uniform in width as shown in Figs. 3 and 4, and where an off center hat crown forming hole 3 is provided in the frame member 1' as shown in Fig. 7, the inner facing strip 4' and the outer facing strip 5' may be correspondingly shaped as indicated in Figs. 8 and 9.

Decorative hats made in accordance with this invention may be economically assembled on sewing and pleating machines in the manner illustrated in Fig. 5. The top facing strip 5—5' and the under facing strip 4—4' are sewn together by a line of stitching 7 which may closely follow the outer rim 2 of the frame member or, if desired, may be sewn through the frame member adjacent the outer rim thereof, thereby providing an outer skirt 8—8' for the under facing strip 4—4' and an outer skirt 9—9' for the top facing strip 5 which extend beyond the outer rim 2 of the frame member. Enhanced decorative values may be obtained by making the under facing strip 4—4' of greater width than the top facing strip 5 so that the skirt section 8—8' of the under facing strip 4—4' as applied to the frame member extends slightly beyond the skirt section 9—9' of the top facing strip 5—5'.

The under facing strip 4—4' and the top facing strip 5—5' are also sewn together by tack stitching 10 directly adjacent the inner rim of the head opening 3 of the frame member so as to form radially extending decorative pleats 11 in the brim areas of the facing strips which cover the brim of the frame member, thereby adding further decorative values to the hat. The inner portions 12—12' and 13—13' of the under and top facing strips 4—4' and 5—5' which extend beyond the inner rim may be pushed through the head opening 3 of the frame member to provide a partial crown for the hat as shown more particularly in Figs. 1 and 6. The crown forming portions 12—12' and 13—13' together provide a heavily pleated crown section when the under and top facing strips are secured together as by the tack stitching 10. Enhanced decorative effects can be obtained by making the under facing strip 4—4' of sufficient width so that the crown forming portion 12—12' thereof extends beyond the crown portion 13—13' of the top facing strip 5—5' as shown in Figs. 5 and 6. The heavily pleated crown portions 12—12' and 13—13' will flex in conformity with

the shape of the wearer's head and thus comfortably cushion the hat on the wearer's head.

The under and upper facing sheets 4' and 5' as shown in Figs. 8 and 9 are applied to the brim forming frame member 1' having an off-center head hole 3 therein in the same manner as shown in Fig. 5, with the outer skirt sections 8' and 9' of the under and top facing strip 4' and 5' extending beyond the outer rim 2 of the frame member 1' and with the inner crown portions 12' and 13' thereof forming the crown section for the hat.

To strengthen the crown portions 12—12' and 13—13' as thus formed, a decorative ribbon 15 may be applied to the outside thereof to provide a hat band as shown in Fig. 1. The ribbon 15 may have a bow 16 formed therein to add further decorative value to the hat. The ribbon 15 may be made in colors which pleasingly contrast with the color of the under and top facing strips. A spray of artificial flowers 17 of contrasting but harmonious color may also be suitably secured to the hat in an artistically arranged manner.

Highly decorative hats for women and children's wear may be made in accordance with this invention by machine operation and at low cost from numerous and various fabrics, plastics, fibers, straws, paperboard, paper and other sheet materials in accordance with the quality and durability desired. Decorative hats made in accordance with this invention are especially adapted for special occasion use such as for wear by women and children in plays and pageants, at birthday and garden parties, weddings and other special occasions where inexpensive but highly pleasing and decorative effects are desired.

While certain novel features of this invention have been disclosed herein and are pointed out in the claims, it will be understood that various omissions, substitutions and changes may be made by those skilled in the art without departing from the spirit of this invention.

What is claimed is:

1. A decorative hat for female wear presenting a brim and a crown with open top, said brim including a brim forming frame member formed from relatively strong sheet material and having an outer rim edge and an inner rim edge which defines a head receiving opening therein, an under facing strip and a top facing strip fully covering the respective under face and top face of said frame member and each having a width substantially greater than the distance between the inner and outer rim edges of said frame member positioned therebetween, said under and top facing strips presenting rim facing portions sewn together around the outer rim edge of the frame member and sewn together adjacent the inner rim edge of the frame member by tuck stitching to thereby form radially extending pleats in the brim areas of the rim facing portions of said strips, said strips also presenting heavily pleated crown portions adapted to extend upwardly from the head opening of the frame member for a sufficient distance to substantially contain that portion of the wearer's head normally projecting above the hat brim to thereby provide a head cushioning support and the open-topped crown for the hat.

2. A decorative hat for female wear presenting a brim and a crown with open top, said brim including a brim forming frame member formed from relatively strong sheet material and having an outer rim edge and an inner rim edge which defines a head receiving opening therein, an under facing strip and a top facing strip of contrasting color fully covering the respective under face and top face of said frame member and each having a width substantially greater than the distance between the inner and outer rim edges of said frame member positioned therebetween, said under and top facing strips presenting rim facing portions sewn together around said outer rim edge by stitching spaced inwardly from the outer free edges of said facing strips to thereby present skirt sections extending beyond the outer rim of the frame member, said rim facing portions also being sewn together adjacent the

adjacent the inner rim edge of the frame member by tuck stitching to thereby form radially extending pleats in the brim areas of the rim facing portions of said strips, said strips also presenting heavily pleated crown portions adapted to extend upwardly from the head opening of the frame member for a sufficient distance to substantially contain that portion of the wearer's head normally projecting above the hat brim to thereby provide a head cushioning support and the open-topped crown for the hat.

10 3. A decorative hat for female wear presenting a brim and a crown with open top, said brim including a brim forming frame member formed from relatively strong and flexible sheet material and having an outer rim edge and an inner rim edge which defines a head receiving opening therein, an under facing strip and a top facing strip fully covering the respective under face and top face of said frame member and each having a width substantially greater than the distance between the inner and outer rim edges of said frame member positioned therebetween, 15 said under and top facing strips presenting rim facing portions sewn together around said outer rim edge of the frame member and sewn together adjacent said inner rim edge of the frame member by tuck stitching to thereby form radially extending pleats in the brim areas of the rim facing portions of said strips, said strips also presenting heavily pleated crown portions adapted to extend upwardly from the head opening of the frame member for a sufficient distance to substantially contain that portion of the wearer's head normally projecting above the hat brim to thereby provide a head cushioning support and the open-topped crown for the hat, and a hat band forming ribbon encircling the crown forming portions of said strips.

4. A decorative hat for female wear presenting a brim and a crown with open top, said brim including a brim forming frame member formed from relatively strong sheet material and having an outer rim edge and an inner rim edge which defines a head receiving opening therein, an under facing strip and a top facing strip fully covering the respective under face and top face of said frame member and each having a width substantially greater than the distance between the inner and outer rim edges of said frame member positioned therebetween, said under and top facing strips presenting rim facing portions sewn together around said outer rim edge by stitching spaced inwardly from the outer free edges of said facing strips to thereby present skirt sections extending beyond the outer rim of the frame member with the skirt section associated with the under facing strip extending beyond the skirt section of the top facing strip, said rim facing portions also being sewn together adjacent the inner rim edge of the frame member by tuck stitching to thereby form radially extending pleats in the brim areas of the rim facing portions of said strips, said strips also presenting heavily pleated crown portions adapted to extend through the head opening of the frame member for a sufficient distance to substantially contain that portion of the wearer's head normally projecting above the hat brim to thereby provide a head cushioning support and the open-topped crown for the hat.

5. A decorative hat for female wear presenting a brim and a crown with open top, said brim including a brim forming frame member formed from relatively strong sheet material and having an outer rim edge and an inner rim edge which defines a head receiving opening therein, an under facing strip and a top facing strip fully covering the respective under face and top face of said frame member and each having a width substantially greater than the distance between the inner and outer rim edges of said frame member positioned therebetween, said under and top facing strips presenting rim facing portions sewn together around said outer rim edge by stitching spaced inwardly from the outer free edges of said facing strips to thereby present skirt sections extending beyond the outer rim of the frame member, said rim facing portions also being sewn together adjacent the

inner rim edge of the frame member by tuck stitching to thereby form radially extending pleats in the brim areas of the rim facing portions of said strips, said strips also presenting heavily pleated crown portions adapted to extend upwardly from the head opening of the frame member for a sufficient distance to substantially contain that portion of the wearer's head normally projecting above the hat brim to thereby provide a head cushioning support and the open topped crown for the hat, the crown portion of said under facing strip projecting beyond the crown portion of said top facing strip.

6. A decorative hat for female wear presenting a brim and a crown with open top, said brim including a brim forming frame member formed from relatively strong but flexible sheet material and having an outer rim edge and an inner rim edge which defines a head receiving opening therein, an under facing strip and a top facing strip of contrasting color fully covering the respective under face and top face of said frame member and each having a width substantially greater than the distance between the inner and outer rim edges of said frame member positioned therebetween, said under and top facing strips presenting rim facing portions sewn together around said outer rim edge by stitching spaced inwardly from the outer free edges of said facing strips to thereby present skirt sections extending beyond the outer rim of the frame member with the skirt section

associated with the under facing strip extending beyond the skirt section of the top facing strip, said rim facing portions also being sewn together adjacent the inner rim edge of the frame member by tuck stitching to thereby form radially extending pleats in the brim areas of the rim facing portions of said strips, said strips also presenting heavily pleated crown portions adapted to extend through the head opening of the frame member for a sufficient distance to substantially contain that portion of the wearer's head normally projecting above the hat brim to thereby provide a head cushioning support and the open-topped crown for the hat, the crown portion of said under facing strip projecting beyond the crown portion of said top facing strip, and a hat band forming ribbon encircling the crown portion of said strips.
